Primary Examiner — Elizabeth J Oswecki(74) Attorney, Agent, or Firm — RALPH E. JOCKE;
WALKER & JOCKE(57) CLAIM

The ornamental design for parcel repository, as shown and described.

DESCRIPTION

A description of the drawings figures is as follows:
FIG. 1 is a front, top, right side perspective view of a parcel repository, showing my new design;

FIG. 2 is a bottom, front, right side perspective view thereof;

FIG. 3 is a right side view thereof;

FIG. 4 is a front view thereof;

FIG. 5 is a left side view thereof;

FIG. 6 is a rear view thereof;

FIG. 7 is a top view thereof; and,

FIG. 8 is a bottom view thereof.

The broken lines in the drawings depict portions of the parcel repository that form no part of the claimed design.
